UNITED STATES PATENT OFFICE.

GERARD SICKELS, OF BOSTON, MASSACHUSETTS.

IMPROVEMENT IN WATER-METERS.

Specification forming part of Letters Patent No. 123,946, dated February 20, 1872.

SPECIFICATION.

I, GERARD SICKELS, of Boston, in the county of Suffolk and State of Massachusetts, have invented certain Improvements in Water-Meters, of which the following is a specification:

Figures 1 and 2 in the drawing are central vertical sections, taken in opposite directions, of my improved meter.

The present invention relates to that class of meters for measuring water or other fluids where a reciprocating motion is given to the pistons; and has for its object the construction and operation of an apparatus at once simple, compact, economical, and efficient. My improvements consist in so arranging and operating a series of devices, to be explained in due course, that water or other fluid introduced into a horizontal cylindrical piston propels it forward, thereby acting on another piston placed above it at right angles so as to partly revolve it, thus opening and closing slots or ports formed in the said pistons, and introducing the pressure alternately on the opposite ends of the pistons, by which means a continuous reciprocating and rocking motion is imparted to the pistons, and the top of an index-shaft connected with the said pistons is so operated as to describe a circle, and the amount of water passing through the apparatus is correctly indicated on the register attached to the meter.

a a a in the drawing represent an outer cylinder or tube formed with slots or ports *b b* opening into an induction-pipe, *c c*, and an eduction-pipe, *d d*, opposite to each other. Above the cylinder or tube *a a a*, and formed at a right angle to it, is another outer cylinder, *e e e*, with slots or ports *f f* arranged on its opposite sides, and connecting with the eduction-pipe *d d* and induction-pipe *c c* by means of the passages *h h* and *i i*. Operating within the outer tubes or cylinders *a a a* and *e e e* are two horizontal cylindrical pistons, *k k k* and *l l l*, arranged transversely with each other, each tube being divided, by a longitudinal horizontal partition, *m m* and *n n*, into two compartments, *o o p p* and *q q r r*. The upper half of one end *s s* of the piston *k k k* is closed, and the other end *t t* is open. The lower half of the piston *k k k* is also arranged with an open

end, *u u*, under the closed end *s s* and a closed end, *v v*, under the open end *t t*. The piston *l l l* is arranged in similar manner with closed ends *w w x x* opposite each other, one above, the other below, and open ends *y y* and *z z* under the closed ends *w w* and *x x*. Each of the compartments *o o p p q q r r* is formed with longitudinal slots or ports *a' b' c' d' e' f' g' h'* formed in each side of the pistons *k k k* and *l l l* above and below the partitions *m m* and *n n*. The pistons *k k k* and *l l l* are formed in the center with vertical shafts *i' k'*, in which operate stems *l' m'*. The stem *m'* is formed with a ball-head, *n'*, working in a socket formed in the bottom of the stem *l'*, which is made with a shoulder bearing on a ball-socket, *p'*, resting on the top of the piston *k k k*, the top of the shaft *l'* being arranged to operate a gauge-index. *q r s t* are cylinder-heads that are readily adjusted to or detached from the cylinders *a a a e e e* by means of the projections or screw-heads *u' w' u' v' v' v' w' w' x' x' x'*, operated by a lever inserted between and bearing against the projections. Inserted in the cylinder-heads *q' r' s' t'* are washers *y' y' z' z' a'' b''*.

The operation of my invention is as follows: Water being admitted through the induction-pipe *c c* passes through the slot or port *b'* into the piston *k k k*, where, pressing against the closed ends *s s v v*, it propels the piston *k k k* forward, thereby operating the stem *l'* by means of the stem *m'* in such a manner as to turn to one side the upper piston *l l l*, and at the same time open the induction-port *f'*, so that the water is admitted to and pushes forward the upper piston *l l l*, which, by means of the stems *l' m'* operating in the shafts *i' k'*, partly revolves the lower piston *k k k* so as to close the induction-port *b'* and open the eduction-port *a'* for the exit of the water. In the meanwhile the same operation opens the induction-tube *d'* in the lower compartment *p p*, so that the water is pressed against the ends *s s v v* in an opposite direction, so as to propel the piston *k k k* backward, and consequently the upper piston *l l l* is turned in a contrary way, thus closing the induction-port *f'* of its upper compartment *q q*, and opening the ports *h'* of the lower compartment *r r*, so that the piston *l l l* is pushed back and the piston *k k k* is

brought to its original position. By continuing the operation above described, a rocking reciprocating motion is produced, whereby an index-hand of a gauge connected with the shaft l' is revolved. The water finds its way to the upper piston $l l l$ through the passage $i i$ and out through the passage $h h$.

Having thus described my improvements, what I claim as my invention, and desire to have secured to me by Letters Patent, is—

1. The manner of introducing the pressure alternately on the opposite ends of the pistons $k k k$ and $l l l$ by means of the semi-rotary motion which each piston imparts to the other, as described, and for the purpose specified.

2. The pistons $k k k$ and $l l l$, arranged at right angles with each other, and provided with compartments $o o p p q q r r$ and slots or ports $a' b' c' d' e' f' g' h'$, substantially as specified.

3. The combination of the upper and lower pistons $l l l$ and $k k k$, arranged and operating at right angles with each other in the cylin-

ders $a a a e e e$, and connected by means of stems $l' m'$, formed with a ball-and-socket joint, substantially as described.

4. The cylinders $a a a$ and $e e e$, arranged at right angles with each other, and formed with passages $h h i i$, substantially as specified.

5. The combination of the cylinders $a a a$ and $e e e$ and passages $h h i i$ with the pistons $k k k l l l$, connected by the stems $l' m'$, and placed at right angles to each other, substantially as specified.

6. The positive reciprocating and rocking motion of the pistons $k k k$ and $l l l$, operating at right angles with each other, producing a perfect revolution of an index-hand attached to a stem, l' , substantially as described.

In testimony whereof I have signed my name to this specification in the presence of two subscribing witnesses.

GERARD SICKELS.
